NONREFILLABLE CLOSURE FOR BOTTLES

Filed May 15, 1937

INVENTOR
Elvyn I. Crutt
BY *Elvyn I. Crutt*
ATTORNEY

This and several other applications for improvements in the construction of closure for bottles, of which the following is a specification.

UNITED STATES PATENT OFFICE

2,118,819

NONREFILLABLE CLOSURE FOR BOTTLES

Elwyn T. Orcutt, East Orange, N. J., assignor of
one-half to Harptone Manufacturing Corpora-
tion, Newark, N. J., a corporation of New York

Application May 15, 1937, Serial No. 142,811

4 Claims. (Cl. 215—23)

This invention relates to improvements in non-refillable closure for bottles, of which the following is a specification.

An object of my invention is to provide a closure which will render the bottle to which it is secured non-refillable, the closure being so constructed as to effectively thwart attempts to refill the bottle by any method and regardless of the position in which the bottle is held.

10 A further object of my invention is to provide a closure which is self-contained and may be conveniently and permanently secured to bottles of any commercial style.

15 A further object of my invention is to provide a closure which consists of few and simple parts, can be manufactured at very low cost, is efficient, positive and tamper-proof in operation and permanent in construction.

These and other advantageous objects, which 20 will later appear, are accomplished by the simple and practical construction, combination and arrangement of parts hereinafter described and shown in the accompanying drawing, forming part hereof, and in which:

25 Fig. 1 is a transverse sectional view of the closure embodying my invention, shown secured to the top of a bottle, the latter being shown fragmentarily, in an upright position, with the closure valve closed.

30 Fig. 2 is a similar view, showing the bottle in a horizontal position, with the closure valve closed.

Fig. 3 is a similar view, showing the bottle in an inverted, pouring position, with the closure 35 valve open.

Fig. 4 is a sectional view taken on line 4—4 of Fig. 3, in the direction indicated by the arrows, and

Fig. 5 is an elevational view of a modified form 40 of counterweight employed in connection with my invention.

As shown in the drawing, the closure 1 of my invention consists essentially of the following: a lower portion of the casing, a cup-shaped tubular member 4 and valve 5 slidably arranged within the casing and confined therein by said ring 3, and a counterweight 6 pivotally connected to the valve 5 by a link 5' or the like, normally firmly seating the valve within the ring.

The ring 3 is preferably provided with a tapered opening 7 therethrough; the valve 5 is preferably correspondingly tapered and is provided with a reduced stem 8 normally passing

through the opening 7 and receiving the link 5' of counterweight 6.

The cup shaped member 4 is hollow and is provided with suitable transverse openings 10. The upper end of member 4 is provided with a circumferential flange 11 of slightly less diameter than the interior of the casing 2 and the lower end thereof is preferably tapered as at 12 to correspond with the tapered opening 7 of the ring 3, to guide the member 4 in its movement within the casing.

The closure 1 is sealed to the top 13 of the bottle B in any desired or convenient manner, after the latter has been initially filled, the contents of the bottle being discharged by merely 15 tilting or inverting the bottle. When the bottle is tilted or inverted the tubular member 4 and valve 5 move away from the ring 3 (see Fig. 3); the contents of the bottle flow through the opening 7 of the ring, through openings 10 of the 20 tubular member 4 and out of the discharge opening 14 at the contracted end 15 of the casing 2.

The lower end 6' of counterweight 6 is preferably weighted so that when the bottle is held in a horizontal position the counterweight will 25 drop to a position within the shoulder portion 16 of the bottle, drawing the valve in a straight line within the ring 3 to close the latter and prevent refilling of the bottle (see Fig. 2), in that position.

If an attempt is made to pump liquid into the 30 bottle while the latter is held in either a tilted or inverted position, the pressure exerted for this purpose will fill tubular member 4 and carry the same upwardly with the valve 5, seating the valve in the ring and thwarting the attempt.

The counterweight 6 may be elongated, as in Fig. 5, to enable it to be used in connection with bottles having shoulder portions of more gradual arcs than that shown in Fig. 2.

I have found the construction above described 40 to be practical and efficient in operation, preventing the refilling of the bottle by any process, including the submersion, pressure, "Beaker" and vacuum processes; my invention prevents refilling the bottle from any position.

The closure 1 may be sealed to the top 13 of the bottle in any desired or convenient manner. For example, the top 13 of the bottle may be provided with a circumferential recess 17 which may be filled with a cementitious material so 50 that when the closure 1 is brought down over the top 13 of the bottle, to rest on shoulder 18, an effective, tamper-proof internal seal will be provided. The closure 1 may be provided with a shouldered portion 19 and the ring 3 may be 55

provided with a circumferential flange 20 adapted to be held between shouldered portion 19 and the top of the bottle. The circumferential flange 20 may be initially sealed within the casing 2 to make the closure self-contained and perfectly sealed, by cementing the circumferential flange 20 of ring 3 to the inside of the casing as shown in the drawing, the cement being indicated by a heavy line 21.

The foregoing disclosure is to be regarded as descriptive and illustrative only, and not as limitative or restrictive of the invention, of which obviously an embodiment may be constructed including many modifications without departing from the spirit and scope of the invention as denoted in the appended claims.

Having thus described my invention, what I claim as new and desire to secure by Letters Patent, is:

- 20 1. In a non-refillable closure for a bottle, a hollow open float member adapted to have sliding movement, and spaced means for restricting the sliding movement of said member, said member being provided with a circumferential flange to guide it in its movement and being further provided with an aperture.
- 25 2. In a non-refillable closure for a bottle, a hollow open float member adapted to have sliding movement, and spaced means for restricting the sliding movement of said member, said member being provided with an aperture.
- 30 3. In a non-refillable closure for a bottle, a hollow open float member adapted to have sliding

movement, spaced means for restricting the sliding movement of said member, a valve, and a counterweight pivotally connected to the valve and adapted to pivot to an offset position within the shouldered portion of the bottle when the bottle is held in a horizontal position, thereby closing the valve and preventing refilling of the bottle.

4. A non-refillable closure for bottles comprising a tubular casing having a contracted end 19 provided with an opening and having an open end adapted to be sealed to the top of a bottle, a ring positioned within the lower portion of the casing, said ring having a tapered opening therethrough, a valve tapered to correspond to the tapered opening of said ring adapted to be guided by and close the opening of said ring, said valve having a reduced stem normally passing through the ring, a cup-shaped tubular member interposed between the ring and the contracted end of the tubular casing, the upper end of said member having a circumferential flange of slightly less diameter than the inside of the casing and the lower end thereof being tapered to correspond to the tapered opening of the ring, to guide said member in its movement within the casing, and a counterweight pivotally connected to the valve and adapted to pivot to an offset position within the shouldered portion of the bottle when the bottle is held in a horizontal position, thereby firmly drawing the valve against the opening of the ring, closing the latter and preventing refilling of the bottle.

ELWYN T. ORCUTT.
